(57) **CLAIM**

The ornamental design for motorcycle front blinkers, as shown and described.

DESCRIPTION

FIG. 1 is a front elevational view of motorcycle front blinkers showing my new design;

FIG. 2 is a side elevational view thereof, the opposite side being a mirror image; and,

FIG. 3 is a close-up perspective view of the right side thereof, the left side being a mirror image.

The broken line showings of the mounting holes on the lights and the remainder of the motorcycle are for illustrative purposes only and form no part of the claimed invention.
